UNITED STATES PATENT OFFICE

107,273

DESIGN FOR A CANOPY

Louis Vavrik, Rossford, Ohio, assignor to The Hettrick Manufacturing Company, Toledo, Ohio, a corporation of Ohio

Application October 19, 1937, Serial No. 72,317

Term of patent 7 years

To all whom it may concern:

Be it known that I, Louis Vavrik, a citizen of the United States and resident of Rossford, county of Wood, State of Ohio, have invented a new, original, and ornamental Design for a Canopy, of which the following is a specification, reference being had to the accompanying drawing, forming a part thereof.

I claim:

The ornamental design for a canopy substantially as shown.

LOUIS VAVRIK.
